DESIGN FOR A HOSE REEL

William H. C. Rehm, South Westerlo, N. Y., assignor to Clifford B. Hannay and Son, Inc., Westerlo, N. Y., a corporation of New York

Application April 26, 1948, Serial No. 145,975

Term of patent 14 years

(Cl. D14—3)

To all whom it may concern:

Be it known that I, William H. C. Rehm, a citizen of the United States, residing at South Westerlo, in the county of Albany, and State of New York, have invented a new, original, and ornamental Design for a Hose Reel of which the following is a specification, reference being had to the accompanying drawings, forming part thereof.

Fig. 1 is a perspective view of one side and the rear of a hose reel, showing my new design;

Fig. 2 is a perspective view showing the front and side of the hose reel opposite to that shown in Fig. 1.

I claim:

The ornamental design for a hose reel, substantially as shown.

WILLIAM H. C. REHM.
